CHARLES D. McCLINTOCK, OF OAKLAND, CALIFORNIA, ASSIGNOR, BY DIRECT AND MESNE ASSIGNMENTS, TO McCLINTOCK ENGINE COMPANY, OF DETROIT, MICHIGAN, A CORPORATION OF DELAWARE.

METHOD OF OPERATING INTERNAL-COMBUSTION ENGINES.

1,234,055.

Specification of Letters Patent. Patented July 17, 1917.

Application filed July 16, 1912. Serial No. 709,627.

To all whom it may concern:

Be it known that I, CHARLES D. McCLINTOCK, a citizen of the United States of America, residing at Oakland, in the county 5 of Alameda and State of California, have invented certain new and useful Improvements in Methods of Operating Internal-Combustion Engines, of which the following is a specification, reference being had 10 therein to the accompanying drawings.

The invention relates to the operation of internal combustion engines by the ignition and combination of the fuel as it is introduced in the engine cylinder. Heretofore 15 internal combustion engines have been operated by several different methods, all belonging to the same type. In one the air for supporting combustion is highly compressed in the engine cylinder during the 20 compression stroke of the piston, and the fuel is then injected to develop the power for the working stroke. Another method is to compress the air and gas externally 25 of the engine and to introduce and burn the gases during the working stroke. The first of these methods has the disadvantage 30 that a full cylinder volume of air is compressed during each cycle without regard to the quantity of fuel that is introduced and burned. This occasions loss of 35 efficiency, particularly where the engine is operating under light loads. With the second method the gases introduced from a storage external to the engine are at low 40 temperature and consequently the combustion is not as rapid or as complete as where they are under the internal heat of the engine.

With the present invention I have overcome 45 both of these objections by proportioning the compressed air in the cylinder during the working stroke to the quantity of fuel introduced, said air being, however, under the high internal heat of the engine and being introduced with the fuel in proportion to the piston displacement during the initial portion of the working stroke. A further feature of the invention is that the air is compressed in the working cylinder, but is ejected therefrom and trapped in proximity thereto, only a portion of the compressed volume being utilized in the working stroke. This results in accumulative pressure in the trapped air which may

be carried to as high a point as desirable, 55 and on account of the proximity of the storage to the engine cylinder the temperature maintained is always high. Still a further feature of the invention is the intimate mixing or commingling of the highly compressed air and fuel as they are introduced 60 into the cylinder, which insures more complete and rapid combustion.

Various constructions may be employed for carrying out my improved method, and 65 in the drawing, I have shown one, the engine being in longitudinal section.

As therein shown A is an engine cylinder; B the piston; C the pitman; and D the crank, all of usual construction. The 70 engine is also shown as of the two-cycle type, and to this end the crank case E is used as a compression chamber for the volume of air which scavenges the burnt gases from the cylinder at the completion of the 75 power stroke, through exhaust ports F and is subsequently compressed.

To control the quantity of air utilized during the power stroke, the clearance space within the engine cylinder is reduced to 80 the minimum and a storage chamber is arranged adjacent to the cylinder and of sufficient volume for holding the compressed air at the desired pressure. This storage chamber G communicates with the cylinder 85 through a passage H and port I, the latter being controlled by an automatic or spring pressed valve J operating as a check. Thus during each compression stroke the volume of air in the cylinder is compressed and 90 will force the valve J from its seat, permitting it to pass into the chamber G, and as the latter is separated from the engine cylinder merely by a partition or division wall K it will be subjected to the internal heat. 95 The air trapped in the chamber G cannot automatically return to the cylinder but a timed valve operating mechanism is provided for lifting the valve J during the initial portion of the working stroke, whereby a portion of the compressed air is permitted to reenter the cylinder. Provision is also made for introducing a proportionate quantity of fuel and, as shown, a second valve L is concentrically arranged within 100 the valve J, and is operated by the same timed mechanism, such as a valve rod M operated by a cam N. Thus whenever the

valve L is unseated by the valve rod it will also lift the valve J and the fuel introduced will be in the center of the stream of air passing through the port I, which will insure intimate commingling of the gases.

Any suitable fuel may be used, but as shown a liquid fuel is first introduced in a chamber O within the valve L, from which it passes by a check valve P into a chamber 10 Q also in the valve. In the latter chamber it is subjected to the high heat developed in the engine and is thus gasified in advance of its introduction into the stream of air.

In operation, during each cycle a full volume of air is compressed and forced into the storage chamber G, the valve J automatically seating. The oil or other liquid fuel is introduced into the chamber O by a suitable pump or other means not shown, from 15 which it passes into the chamber Q and is gasified.

During the working stroke both valves J and L are unseated which permits the compressed air with a proportionate quantity 25 of the gas to enter the cylinder, moving the piston by the initial pressure which is maintained by the combustion of the gases. In starting an igniter such as R is used for igniting the gases, but when the engine is 30 in full operation the high pressure and high temperature will cause automatic ignition upon introduction of the gases.

After the piston has traveled a portion of the power stroke, the valves J and L are 35 closed and the point of cut-off may be varied to suit the requirements of the load. Thus the gases will operate expansively during the remainder of the power stroke to secure the greatest efficiency.

40 As a full cylinder volume of air is compressed during each cycle and trapped in the chamber G, while only a portion of this volume is permitted to enter the cylinder chamber, it is obvious that the pressure in 45 the chamber G will rise until the desired limit is obtained. This limit is preferably set at the point of greatest efficiency while any further compression may be exhausted through an automatic valve S or in any 50 other way.

While I have shown the one form of apparatus it is obvious that the same method may be employed with various constructions in which provision is made for the control 55 of the compressed air and for trapping the

same where it will be under the internal heat of the engine cylinder.

What I claim as my invention is:

1. The method of operating internal combustion engines, comprising the storing of 60 compressed air under the internal heat of the engine cylinder and separate therefrom, in establishing communication between the stored air and the cylinder during the initial portion of the working stroke, in commingling with the admitted stream of air a proportionate quantity of fuel to cause combustion controlled by the piston displacement, and in cutting off the supply after a portion of the piston stroke to utilize the gases expansively.

2. The method of operating internal combustion engines, comprising compressing in the engine cylinder a volume of air during each compression stroke and ejecting and trapping the successive volumes in proximity to and under the internal heat of said cylinder, and in re-admitting to the cylinder a variable portion of the trapped air 75 commingled with fuel during each working 80 stroke.

3. The method of operating internal combustion engines, comprising the compression and ejection of equal amounts of air during each compression stroke, the trapping of 85 successive ejections in proximity to and under the internal heat of the engine, and in re-admitting to the engine cylinder variable 90 quantities of the trapped air commingled with fuel during working strokes, the variations being compensated for by a change in pressure of the trapped air.

4. The method of operating internal combustion engines, which comprises compressing 95 air in the working cylinder, storing air so compressed in a chamber in proximity to the engine cylinder and under the internal heat thereof, in returning air from said chamber to the working cylinder, in controlling the return of the air by a variable 100 time means, and in commingling exteriorly of said chamber with the air returned a quantity of fuel.

In testimony whereof I affix my signature in presence of two witnesses.

CHARLES D. McCLINTOCK.
